UNITED STATES PATENT OFFICE.

FREDERICK IDDO CASS, OF CLINTONVILLE, WISCONSIN, ASSIGNOR OF ONE-HALF TO EDWARD FELSCHOW, OF CLINTONVILLE, WISCONSIN.

LEVELING DEVICE FOR BOILERS.

No. 858,382.

Specification of Letters Patent.

Patented June 25, 1907.

Application filed March 25, 1907. Serial No. 364,523.

To all whom it may concern:

Be it known that I, FREDERICK IDDO CASS, a citizen of the United States, residing at Clintonville, in the county of Waupaca and State of Wisconsin, have invented certain new and useful Improvements in Leveling Devices for Boilers, of which the following is a specification.

This invention is a leveling device for the boilers of portable or traction engines, and has for its object to provide an improved device of this kind, together with means for operating the same by the engine.

The invention comprises a series of independently operated jack-screws on which the boiler is mounted, and a gearing between the jack-screws and the crank-shaft of the engine.

In the accompanying drawings, Figure 1 is a plan view. Fig. 2 is a side elevation. Fig. 3 is an elevation taken from the opposite side. Fig. 4 is a detail.

Referring specifically to the drawings, 10 denotes the boiler of a portable traction engine. The boiler is mounted on jack-screws one of which is located at the front end, and one on each side at the rear end of the boiler.

To the top of the boiler at its front end is bolted or otherwise secured a bracket 11 having a head 12 provided with a vertical guide-opening through which the front jack-screw 13 loosely passes. The screw-stem has a squared portion 14 which passes through a vertical guide-opening in a bracket 15 secured to the bottom of the boiler and projecting in front thereof. On the screw-stem is mounted a nut 16 the top of which bears against the head 12 whereby the front end of the boiler will be raised or lowered when 40 said nut is caused to travel up or down on the screw, the latter being prevented from turning by the squared portion 14. The nut 16 is in the form of a worm-wheel which meshes with a worm 17. The shaft of the 45 worm is in two sections indicated at 18 and 19, respectively. The section 18 is journaled in suitable bearings in the bracket 11 and carries the worm 17. To one end of the shaft-section 19 is fixed an upstanding arm 50 20 which is hung on a pin 21 projecting from a standard 22 secured to the top of the boiler. The arm 20 is slotted as at 23 to receive the pin 21. The opposite end of the shaft-section 19 is connected by a universal

joint 24 to the shaft-section 18. On the shaft-section 19 is a worm-wheel 25 which meshes with a worm 26 on the crank-shaft 27 of the engine 28. To the arm 20 is pivoted one of the members of a pair of toggle-arms 29, the other arm being pivoted to a bracket 30 secured to the side of the boiler. The operating-rod 31 of the toggle extends to the rear end of the boiler so as to be within easy reach of the attendant. When the rod is pushed forwardly the toggle-arms are straightened out which raises the shaft-section 19 and throws the worm 26 and worm-wheel 25 into gear. When the rod is pulled rearwardly the toggle-arms recede from each other which lowers the shaft-section 19 and throws the worm 26 and worm-wheel 25 out of gear. The purpose of the universal joint 24 between the shaft-sections is to permit this movement of the shaft-section 19.

On top of the boiler at the rear end there is secured a saddle 32 which projects from the sides of the boiler and has vertical openings through which the rear jack-screws 33 and 34, respectively, loosely pass. The screw-stems are squared as indicated at 35 and 36, respectively, in the same manner as the front screw-stem, and said squared portions pass through vertical guide-openings in a bracket 37 secured to the bottom of the boiler at its rear end and projecting from the sides thereof.

The nuts which travel on the rear jack-screws are indicated at 38 and 39, respectively, they being in the form of bevel gears, and are mounted on the screw-stems between the saddle 32 and a plate 40 which is connected by rods 41 with the bracket 37. The plate 40 has vertical openings through which the screw-stems loosely pass. When the nuts 38 and 39 are turned they travel up or down on the screw-stems and by their engagement with the plate 40 they will raise or lower the rear end of the boiler. The screw-stems are prevented from turning by their squared portions. The plate 40 also has openings 42 to receive bevel pinions 43 and 44, respectively, which mesh with the gear-wheels 38 and 39, respectively. The shaft of the pinion 43 is in two sections indicated at 45 and 46, respectively, the former being journaled in suitable bearings in the plate 40. The shaft-section 46 is supported at one end in a vertically movable bearing-block 47,

and at the opposite end is connected to the section 45 by a universal joint 48. The bearing-block 47 is mounted on a standard 49 projecting from the bearing 50 of the crank-shaft 27 by means of pins 51 projecting from said block into slots 52 in said standard. On the shaft-section 46 is a worm-wheel 53 which meshes with the worm 26. The worm-wheel 53 and the worm 26 are thrown 10 into and out of gear by toggle-levers 54 pivoted respectively to the block 47 and a bracket 55 secured to the boiler. The toggles are operated by a rod 56 in the same manner as the toggles 29. This rod also extends to the rear end of the boiler within easy reach of the attendant. The shaft of the bevel pinion 44 is also in two sections indicated at 57 and 58, respectively, which are mounted and operated in the same manner 15 as the shaft-sections 45 and 46. The worm-wheel 59 on the shaft-section 58 meshes with a worm 60 on the crank-shaft 27 at the opposite end from the worm 26. A toggle 61 and operating-rod 62 for throwing the worm 25 60 and the worm-wheel 59 into and out of gear are also provided, these parts being mounted and operated in the same manner as the toggles heretofore described.

In order to provide a firm foundation for 30 the jack-screws, they are fitted with shoes 63 which are serrated on the bottom as at 64 to prevent slipping. The shoes have vertical openings 65 into which the screw-stems extend and in which they are pivotally secured 35 by transverse pins. The pivot pin 66 of the front jack-screw is arranged lengthwise with respect to the boiler, and the pivot pins 67 of the rear jack-screws are arranged transversely with respect to the boiler by reason 40 of which the shoes will accommodate themselves to uneven ground. This arrangement, together with the fact that each jack-screw can be operated independently also permits the boiler to be tilted to one side by 45 operating either one of the rear jack-screws, and also to be tilted forwardly or rearwardly by operating the front jack-screw. It will therefore be seen that the device has a wide range of usefulness and enables the boiler to 50 be accurately leveled.

I claim:—

1. The combination with a boiler, an engine mounted thereon, and its crank-shaft, of a bracket on the boiler and having a verti-

cal opening, a screw-stem passing through 55 said opening, a traveling nut on the screw and engageable with the aforesaid bracket, said nut being in the form of a worm-wheel, a counter-shaft having a worm meshing with the worm-wheel, a worm-wheel on the counter-shaft, and a worm on the crank-shaft meshing with the last mentioned worm-wheel.

2. The combination with a boiler, an engine mounted thereon, and its crank-shaft, 60 of a bracket on the boiler and having a vertical opening, a screw-stem passing through said opening, a traveling nut on the screw and engageable with the aforesaid bracket, said nut being in the form of a worm-wheel, a 65 sectional counter-shaft, a universal joint connecting said sections, a worm on one of the sections meshing with the aforesaid worm-wheel, a worm-wheel on the other shaft-section, a worm on the crank-shaft meshing with 70 the last mentioned worm-wheel, and means for throwing the last mentioned worm and worm-wheel out of gear.

3. The combination with a boiler, an engine mounted thereon, and its crank-shaft, of 75 a screw-stem, a traveling nut on the screw, said nut being in the form of a bevel gear, an abutment carried by the boiler and engageable by the nut, a counter-shaft having a bevel pinion meshing with the aforesaid gear, 80 a worm-wheel on the counter-shaft, and a worm on the crank-shaft meshing with the worm-wheel.

4. The combination with a boiler, an engine mounted thereon, and its crank-shaft, of 85 a screw-stem, a traveling nut on the screw, said nut being in the form of a bevel gear, an abutment carried by the boiler and engageable by the nut, a sectional counter-shaft, a universal joint connecting said section, a bevel pinion on one of the sections meshing with the aforesaid gear-wheel, a worm-wheel on the other section, a worm on the crank-shaft meshing with the worm-wheel, and means for throwing said worm 90 and worm-wheel out of gear.

In testimony whereof I affix my signature, in presence of two witnesses.

FREDERICK IDDO CASS.
